UNITED STATES PATENT OFFICE.

MATTHEW P. BENSON, OF TROY, AND MILTON M. WIENER, OF NEW YORK, N. Y.

STRAP ATTACHMENT FOR BRUSHES.

1,386,756.

Specification of Letters Patent.

Patented Aug. 9, 1921.

Application filed March 16, 1921. Serial No. 452,855.

To all whom it may concern:

Be it known that we, MATTHEW P. BENSON and MILTON M. WIENER, citizens of the United States, residing, respectively, at 5 Troy, in the county of Rensselaer and State of New York, and New York city, in the county of New York and State of New York, have invented certain new and useful Improvements in Strap Attachments for 10 Brushes, of which the following is a specification.

This invention relates to brushing and scrubbing, and has particular reference to means for detachably securing a handle or 15 strap to the back of a brush.

Among the objects of the invention is to provide a means for attaching a strap or handle to the back of a bath brush or its equivalent, enabling the strap to be readily 20 adjusted as to length whereby it may be made to fit any size of hand.

Another object of the invention is to provide for a bath brush, a strap attachment adapting the strap to be used by one who 25 desires a strap on the brush or to be disconnected for the use of the brush by one who does not like a strap.

A still further object of the invention is to provide a strap attachment through which 30 the strap or handle may be readily attached to the brush at any time after the brush is finished.

Yet another object is to not only simplify and cheapen the strap mechanism, but also 35 to generally improve the same along the lines of neatness of appearance and facility of adjustment.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had to the accompanying drawings, in which like 45 reference characters designate the same parts in the several views, and in which—

Figure 1 is a plan view of a brush with 50 the invention shown applied.

Fig. 2 is an end view of the same.

Fig. 3 is a vertical sectional detail on the line 3—3 of Fig. 1.

Fig. 4 is a detail perspective view of one 55 of the clips detached.

Referring now more specifically to the

drawings A is the back of a brush B of any suitable size, design, construction or purpose, but as indicated the brush is one designed for bath purposes and whose back A is made 60 of laminated water proof material, the several layers being vulcanized together permanently for the purpose of locking the bristles in place.

In the practice of this invention the brush 65 is made and finished independently of the strap. Moreover, the strap 10 consists of but a single piece of material, the length of which may be varied at any time by any user of the brush, and being removable readily 70 from the brush may be sterilized if desired independently of the brush, or a new strap may be provided made of any convenient flexible material and attached readily to the brush when required. 75

The attachment means consists of a pair of clips 11 preferably of metal or of any other suitable stiff strong material.

Each strip is stamped or otherwise conveniently formed from sheet material such 80 as a non-corrodible metal and comprises three main parts as follows,—a side panel 12, and upper and lower flanges 13 and 14, both integral with the side panel and extending thence in the same direction parallel to each 85 other and at right angles to said panel.

The side panel 12 is provided with a pair of slots 15 extending parallel to the flanges. The end of the strap is threaded inward through the lower slot, thence outward 90 through the upper slot, and passes thence upward over the upper flange and is gripped and so held at any desired length by the action of the main or loop portion of the strap in practice. Any tension or pull upon 95 the loop of the strap is exerted upward or perpendicular to the upper surface of the back and so it is impossible for either end of the strap to slip along the slots or clip while the brush is in use. The length of the strap, 100 however, may be varied when desired by simply pulling lengthwise on either portion of the strap according to whether the strap is to be lengthened or shortened in effect, and this adjustment may be effected without disconnecting the clip from the brush although naturally it is performed somewhat easier when the clips are detached. 105

Any suitable means may be provided to secure the clips detachably to the brush back 110 A. To this end each of the flanges 13 and 14 is provided with relatively sharp means

to project or bite into the structure of the back. Thus the flanges are shown provided with sharp edges or teeth 13' and 14' respectively. It is to be noted also that the flange 14 is materially wider than the upper flange,—primarily to facilitate the connection and disconnection of the clips, but secondarily to present a smoother finish for that portion of the brush upon which the operator's hand is guided in slipping it beneath the strap.

With the ends of the strap threaded through the clips as indicated, the brush having been made and finished, the clips are attached to the brush by the following simple expedient. The longer flange 14 is applied full-width against the lower or under surface of the back A, its tooth 14' engaging into said surface. The operator then suitably holding the brush in both hands, so manipulates the clip with his thumbs and fingers as to force the narrower flange 13 over the upper edge of the back, the material of the back being sufficiently compressible during this action to cause the tooth 13' to pass over the edge aforesaid and bite somewhat into the surface. As above promised the strain or pull on the strap is either upward perpendicular to the lower flange 14 or else slightly inward toward the other side of the brush. Hence in practice there is no tendency for either clip to be separated from the back. When, however, the strap is to be detached from the brush either clip may easily be detached by simply pulling outward on its upper portion, swinging it around the tooth or sharp edge 14' as an axis.

It will be noted that the clips are of a very simple, cheap and indestructible character, and that the strap 10 may be of braid,

tape, or any other suitable flexible material, it being essential only that it be of a nature adapted to be threaded through the slots as indicated.

45

We claim:

1. The herein described clip for the attachment of a strap to a brush, the same comprising a single piece of sheet material consisting of a vertical side panel to lie close against the edge of the brush back and having a pair of slots formed therein, and a pair of upper and lower flanges extending horizontally from the side panel parallel to each other.

55

2. A device as set forth in claim 1 in which one of the flanges is wider than the other.

60

3. A device as set forth in claim 1 in which the lower flange is wider than the upper flange, and both flanges are provided with means to bite into the brush back.

65

4. The combination with a brush back having a smooth unbroken edge and a one piece strap to constitute a handle for the back, of means to detachably secure the end portions of the strap to said smooth edge of the back, said means comprising a pair of clips each having a side portion with slots through which an end of the strap may be threaded and held snugly against the edge of the brush back, the free end being adjacent to the upper edge of the clip and inside of the main loop portion of the strap, said clip including also integral members embracing the smooth edge of the back and engaging the upper and lower surfaces thereof.

70

In testimony whereof we affix our signatures.

MATTHEW P. BENSON.
MILTON M. WIENER.
